UNITED STATES PATENT OFFICE.

DAVID WALKER AND FRANK H. HOWARD, OF NEWARK, NEW JERSEY; SAID
HOWARD ASSIGNOR TO SAID WALKER.

DESIGN FOR A STAIR-CARPET BUTTON.

SPECIFICATION forming part of Design No. 20,540, dated March 3, 1891.

Application filed February 4, 1891. Serial No. 380,235. Term of patent 7 years.

To all whom it may concern:

Be it known that we, DAVID WALKER and FRANK H. HOWARD, citizens of the United States, residing at Newark, in the county of

- 5 Essex and State of New Jersey, have invented and produced a new and original Design for Stair-Carpet Buttons; and we do hereby declare the following to be a full, clear, and exact description of the invention, such as will enable others skilled in the art to which it appertains to make and use the same, reference being had to the accompanying drawings, and to letters of reference marked thereon, which form a part of this specification.
- 10 15 In the accompanying drawings, which are deemed sufficient to illustrate the invention, Figure 1 is a front elevation of the newly-designed stair-carpet button; and Fig. 2 is a section of the same, taken on line x.
- 20 25 The leading feature of the design consists in a stair-carpet button, which presents to view in front elevation petal-like configurations radiating from a center, alternating with which are ornaments resembling scallop-

In said drawings, a indicates a carpet-fastening button, the outer edges of which are turned rearward, as indicated in Fig. 2.

a' a' are petal-like configurations radiating 30 from the center, and c c are alternating ornaments resembling scallop-shells appearing between the said petal-like configurations.

What we claim as new is--

The design for a stair-carpet button herein 35 described, consisting of a stair-carpet button having the radial petal-like ornaments and the intervening shell-like ornaments, substantially as set forth and shown.

In testimony that we claim the foregoing 40 we have hereunto set our hands this 16th day of January, 1891.

DAVID WALKER.
FRANK H. HOWARD.
